UNITED STATES PATENT OFFICE.

DAVID D. BUICK, OF DETROIT, MICHIGAN.

DESIGN FOR A BATH-TUB RIM.

SPECIFICATION forming part of Design No. 26,083, dated September 22, 1896.

Application filed August 5, 1896. Serial No. 601,819. Term of patent 14 years.

To all whom it may concern:

Be it known that I, DAVID D. BUICK, a citizen of the United States, residing at Detroit, in the county of Wayne and State of Michigan, have invented and produced a new and original Design for Bath-Tub Rims, of which the following is a specification, reference being had therein to the accompanying drawings, in which—

10 Figure 1 is a top plan view of a bath-tub rim of my design, and Fig. 2 is a side or edge elevation thereof.

15 The leading feature of the design is the configuration of the rim, comprising a substantially rectangular section with one rounded end and a ring or oval, into which the sides merge at the opposite end.

The rim comprises the side bars A, connected at one end by the curved end section B and at the opposite end having the bends C, which connect with and merge into the opposite points on the oval or ring shaped section D. The rim has the exterior curved or rounded face, as shown in Fig. 2.

What I claim as my invention is—

25 The design for a bath-tub rim substantially as herein described and shown.

In testimony whereof I affix my signature in presence of two witnesses.

DAVID D. BUICK.
